UNITED STATES PATENT OFFICE.

BURNHAM C. STICKNEY, OF ELIZABETH, NEW JERSEY, ASSIGNOR TO UNDERWOOD COMPUTING MACHINE COMPANY, OF NEW YORK, N. Y., A CORPORATION OF NEW YORK.

COMPUTING MACHINE.

Application filed July 19, 1922. Serial No. 576,024.

To all whom it may concern:

Be it known that I, BURNHAM C. STICKNEY, a citizen of the United States, residing in Elizabeth, in the county of Union and State of New Jersey, have invented certain new and useful Improvements in Computing Machines, of which the following is a specification:

This invention relates to computing mechanism, and has principally to do with setting the mechanism to perform either subtraction or addition at will, particularly where two or more registers are employed in the same machine, as, for example, in the patents to 15 Minton, No. 1,280,065, of September 24, 1918, and Thornton, No. 1,283,360, of October 29, 1918.

In the Underwood combined adding and typewriting machine to which said patents relate, the dial or number-bearing wheels advance in the same direction when subtracting as when adding, subtraction being performed by adding complements. The type-keys set up index-pins corresponding to the 25 number being typed on the work-sheet; then a general operator serves to advance the dial-wheels according to such setting of the index-pins. When desired, the mechanism of said machine is shifted to a subtraction condition preparatory to the typing of the number on the work-sheet, and each digit type-key may then set up a complementary index-pin, so that at the operation of the general operator the dial-wheels are advanced in such 30 a manner that the number typed on the work-sheet is subtracted from the number previously in the register, as set forth in the Hanson Patent, No. 1,278,812, of September 10, 1918. It is usual to shift the entire adding mechanism to subtraction condition, so that the registers must either all add or all 35 subtract.

One of the objects of the present invention is to provide individual subtraction shifts 45 for the registers, so that while one or more registers are set for addition, one or more other registers may be set for subtraction, thus providing for simultaneous addition and subtraction in a machine in which subtraction 50 is performed by the complementary addition method. Certain of the features of improvement may also be used in single-register machines.

Usually each register is provided with a system of depressible indexing pins. These 55 are set by means of linkages which are connected one to each digit key. Each linkage usually comprises a bar extending horizontally across the machine and depressible to set the selected index-pin.

According to the present invention, each key is provided with a double linkage, so that it depresses two bars, one bar being capable of setting an index-pin, for addition, and the other bar being capable of depressing the complementary index-pin, for subtraction. For example, if key "2" is operated a "2" bar is depressed, also a "7" bar.

However, only one of said bars is effective, the other bar operating idly. The matter of 70 which bar shall be active and which idle is determined by shifting a subtraction lever preparatory to operating the type-keys.

Each of these setting bars carries a comb whose teeth project downwardly to set the 75 indexing pins. These combs extend longitudinally of the bars and are endwise shiftable, and the comb-teeth may be shifted to position where they will move down idly between the files of pins. A single comb-shifter 80 is employed at each register for all of the combs; and by its use the addition combs may be shifted out of use and the subtraction or complementary combs may be simultaneously shifted into use. Any one or more 85 registers may be in addition condition while any one or more other registers may be in subtraction condition. Subtraction may be performed in only one register at a time, so that it is unnecessary to put all of the register 90 through a subtraction operation idly, while subtraction is being performed in only one of the registers.

Other features and advantages will hereinafter appear.

In the accompanying drawings,

Figure 1 is a fragmentary view, in longitudinal section from front to rear through a pair of linkages, each linkage capable of setting the same pin, one linkage (operated by 100 one key) setting it for addition, and the other linkage (operated by another key) setting it for subtraction.

Figure 2 is a sectional elevation of an Underwood combined typewriting and adding machine, taken from front to rear,

2
Figure 3 shows the usual supernumerary bar that is associated with each register for effecting the automatic insertion of an extra "1" in the units position at each subtraction operation.

Figure 4 is a sectional plan of the middle portion of the adding mechanism, showing the lower bars of the linkages, these bars carrying at their under edges the combs which set the index-pins.

Figure 5 is a cross-section of the machine, showing the bars which carry the index-pins and drive the dial wheels, also the rock-shafts operable by the digit keys, and certain of the linkages which are operable by the rock-shafts and carry endwise shiftable combs for setting the index-pins.

Figure 6 is a plan of the so-called index-pin-setting frame, which is seen in cross-section at Figure 5.

Figure 7 is a diagrammatic plan of the index-pin-setting mechanism.

Figure 8 is a perspective skeleton view to illustrate the relationship of the key-operated linkages, the setting-combs thereon, the index-pins, the comb-shifting mechanism, etc.

Figure 9 is a sectional side elevation, showing the subtraction-setting key and means operable thereby for restoring the "9" pins which were set by the general operator at the completion of the last subtraction operation.

As set forth in said patents, when any one of the digit-type-keys 10 is depressed to impress its type 11 upon the paper, a stem 12 pendent from said key depresses an arm 13 upon a horizontal rearwardly-extending rock-shaft 14. There are nine of these rock-shafts 14, one for each digit key. These rock-shafts do not need to shift endwise, as in said patents; but fixed upon each is both an addition arm 15 for setting the index pin that corresponds with the key and a subtraction arm 16 for setting complementary index pins. For the shaft 14 belonging to the key "4," the rock arms may be merged into one, 15, which is connected to operate adjoining linkages, the front linkage being for addition and the rear linkage for subtraction. The shaft 14 for key "9" has only an addition arm 15.

Each of the arms 15, 16 is slotted to engage a pin 17 projecting from a horizontal transverse rod 18 forming an upper member of a linkage, said rod being pivoted to short arms 19, 20 rising from left-hand and right-hand pivot rods 21 fixed in the framework 22. Said short arms are joined to leftwardly-extending arms 23, upon which are pivoted by their ends horizontal transverse pin-setting bars 24, for addition, and 25 for subtraction. When the upper rod 18 of the linkage is moved endwise by its key, the lower bars 24, 25 are moved down-

wardly, and one of them depresses a selected index-pin 26.

Systems of index-pins or devices 26 are illustrated, one for each register. The pins are disposed as usual in denominational files and transverse digit-rows. The pins in each denomination are mounted in the usual manner upon a forwardly-extending horizontal bar 27, having at its front end a rack 28 to drive the dial wheel 29, of which several compose the register. As usual, whenever the typewriter carriage 30 is nearing a given denominational position, a dog 31 on said carriage operates to lift a pivoted jack 32, whose rear end depresses a rod 33, thereby operating a lever 34, which by means of a transposition device 35, is effective to displace forwardly a bar 27 of a denomination corresponding to the position of the typewriter carriage. This brings the index-pins on said bar 27 to position beneath the key-operated setting bars 24, 25, which extend across the machine, and hence there may be depressed or set any selected pin 26 upon the forwardly-displaced pin-bar 27.

Inasmuch as each of the first eight key-operated rock-shafts 14 operates two of the linkages, it follows that two of the pin-setting bars 24, 25 are depressed. Either one bar or the other may be effective, according to whether the individual register is set for addition or subtraction.

To permit such altering of the condition of any register mechanism, each of the depressible bars 24, 25 is provided with a displaceable pin-setting comb. Each addition comb comprises a strip 36 having pendent teeth 37, which are spaced evenly to agree with the transverse spacing of the index-pins 26, forming the system. Each subtraction comb comprises a strip 38 and teeth 39. Several of the combs may be provided upon each of the depressible bars 24, 25, one comb for each register. Any comb may be shifted longitudinally upon its bar. This shifting may be independent of the other combs on that bar. Hence one or more registering mechanisms may be set for subtraction, while the remainder are set for addition.

Each of the depressible bars 24, 25 is preferably provided with longitudinal slots 40, in which the combs, by means of ears 41 thereon, are carried up and down. These slots are open at the bottom, and the comb teeth project below the bar. The slots 40 are so long as to permit the necessary endwise shifting of the combs.

All of the combs for any one register are shiftable simultaneously by means of a shift bar 42, which extends horizontally from front to rear through aligned slots or apertures 43, in all the combs in any system. These shift bars are supported upon arms 44 which depend from rock-shafts 45, that

extend horizontally from front to rear, these rock-shafts being operable in a manner presently to be explained. In Figure 5, at the left hand, the combs are illustrated in position for subtraction, while the middle and right-hand combs are indicated as in position for addition. The teeth 37 in the addition combs align with the spaces between the teeth 39 in the subtraction combs; and hence in the left-hand register at Figure 5 all of the addition teeth 37 are in position to drop down between the rows of index-pins 26 and are hence out of use; while in the other two registers all of the addition teeth 37 are positioned directly over the index-pins 26, and hence are effective upon the operation of the keys, while the teeth 39 move idly down between the pins. Thus, in the left-hand register the operation of each key will set up its complementary pin 26, for subtraction, while in the other two registers the same key will simultaneously set up pins 26 for addition.

The typewriter carriage may be provided with three of the denomination-selecting dogs 31, 46, 47, and the sets of jacks 32 may have a corresponding echelon arrangement as usual so that computation may be carried on in all three registers at one typing of a number on the work-sheet. Many other arrangements may also be used, as for example there may be one selecting dog 31 and three similar sets of jacks, so that only one register is affected at each typing of a number; and in such a case all the numbers in one column may be subtracted, while those typed in the other two columns on the work-sheet may be added, without the necessity of requiring the operator to shift from addition to subtraction in every line of typing.

Each comb may have the same thickness as the bar 24 or 25 in which it is mounted; and both the bars and the combs may be guided in vertical slots 48 formed in a number of guide-plates 49 arranged on edge and extending from front to back of the sets of systems of index-pins and fixed by ears 50 to the framework 22 of the machine. The bars 24, 25 are placed in pairs, face to face. The arrangement of bars and combs in face-wise contact permits of loose guiding, so that bars and combs work freely, while there is no liability of any of them getting out of order from accumulation of dirt or other causes. The combs may be loosely supported upon their supporting bars so that there will be no binding of the combs in said slots 40. The guide-plates 49 may be placed just outside of the sets of pin-bars 27 and where each slot in each plate will serve as a guide for two of the transverse bars 24, 25, as well as the two combs 36, 38 mounted thereon. This secures inexpensively a desirable facewise compact-

ness of the moving parts, and the combs are properly confined while free to move endwise and vertically. By placing the combs closely face to face, their teeth may strike fairly upon the tops of the index pins, since the thickness of one comb, added to that of the contiguous comb, may just equal the diameter of the pin beneath, so that the operation of said pin is assured by any of the combs intended therefor.

At the depression of any key, only one of the bars 24, 25 in any contiguous pair is depressed. That is to say, the two bars 24, 25, which are depressed at the operation of each key, are found in different pairs. For example, the digit keys for "1" and "8" depress bars in the first and eighth pairs, counting from the front; the keys "2" and "7" depress the bars in the second and seventh pairs; the keys "3" and "6" in the third and sixth pairs; the keys "4" and "5" in the fourth and fifth pairs; and so on. The bell-cranks 19, 23 and 20, 23 are likewise placed in pairs at the ends of the linkages, Figure 6.

At its rear end each of the subtraction-shifting rock-shafts 45, Figure 4, has an arm 51 extending towards the right and depressible by means of a link 52, Figure 2, which, at its lower end, is pivoted to a rock-arm 53 fixed upon a transverse horizontal rock-shaft 54, the latter having fixed thereto an upright arm 55, to which is connected the rear end of a bar 56 carrying a shift-key 57, so that, by pushing back said bar, the shaft 54 is rocked, and the arm 53 is moved down, together with the link 52, thereby pulling down the arm 51 and rocking the shaft 45, which causes the bail 42, 44 to rock or shift to the left, thus shifting all of the combs to bring the subtraction teeth 39 into use and the addition teeth 37 out of use, and hence setting the individual register for subtraction, as at the left-hand portion of Figure 5.

Since "9" has no complement, the "9" pins are not to be depressed by any digit-key when a register is in subtraction condition. Hence but a single bar 24 is used for depressing the "9" pins in addition, said bar connected to the "9" key. However, in the operation of setting a register to subtraction, the "9" pins are all depressed automatically. In the course of the subsequent subtraction operation, any of the depressed "9" pins may be restored by any of the type-keys "1" to "8," all of which are capable of operating a special transverse bar 58, whose function it is to restore the "9" pin in any denomination. Hence, when any pin "1" to "8" is set in any denomination, the "9" pin in the same denomination is simultaneously restored. Said special bar 58 is provided with index-setting combs 59 similar to those already mentioned. Each

of these combs 59 is shifted endwise into use automatically when its register is being set for subtraction, and is shifted out of use automatically when the register is being set for addition. Any register may be set independently of the other registers, by pressing its subtraction key 57, which is similar to those in use on said Underwood machine; said key performing its usual general function and also serving to shift the pin-setting combs 36, 38 from addition position to subtraction position for that register.

One subtraction key is usually employed 15 on the Underwood machine for setting all of the registers simultaneously to subtraction; but according to the present improvements the subtraction keys 57 may be individual to the registers. However, one subtraction key may set a plurality of registers to subtraction, if desired, while any one or more registers remain at addition position.

The rock-shaft 54, to which a subtraction key is connected, has in each instance a mechanism connected thereto for setting all of the "9" index pins of its register. Said "9" pins are usually loosely connected to levers 60 that are pivoted individually upon the pin-bars, so that the "9" pins may be depressed 30 or lifted by means of said levers. A universal bar 61 is provided for each register, and extends across the set of levers 60 for depressing the same, said universal bar or bail being fixed by arms 62 upon a transverse 35 horizontal rock-shaft 63 journaled in the framework, as set forth in said Minton Patent 1,280,065. From the rock-shaft extends downwardly and rearwardly an operating arm 64.

As set forth in said Minton patent, a subtraction bar 69, extending forwardly and rearwardly alongside of a set of pin-bars 27, is normally locked in forward position, against the tension of a spring 70, by means 45 of a detent 71, which hooks into a notch 72 provided in said subtraction bar 69. The detent may be released for the purpose of permitting the spring 70 to draw back the subtraction rod 69. For this purpose the detent is secured to the shaft 54, which is rocked by the arm 55 and subtraction key-rod 56 against the tension of a returning spring 75, the latter connected to arm 55, Figure 2. When a subtraction key 57 is 55 pressed back, the shaft 54 is rocked, removing the detent 71 from the notch 72 and permitting the spring 70 to draw back the subtraction bar 69. A hook 81, pivoted on the subtraction bar 69, catches upon a projection 60 82 formed on the arm 64, and thus rocks the shaft 63 and the bail 61, causing the latter to descend and depress the forward ends of levers 60 and thus set all the "9" pins in that register. Before the subtraction bar 69 completes its rearward stroke, an arm 78 on the

hook 81 will come into engagement with a stop or disconnector 84, whereby the hook 81 will be rocked against the tension of a spring 85 out of engagement with the projection 82, thus permitting the spring 79 to 70 retrieve the bail 61, 62, and leaving the "9" pins and their levers 60 free and clear in their set positions. The bail arm 64 may be provided with the usual extension 86, where by the bail may be restored by the general 75 operator of the machine should necessity arise.

When the "9" pins are in depressed positions, the rear ends of their individual levers 80 are in elevated positions beneath the special transverse setting bar 58, which is carried by a linkage which resembles one of the previously described linkages and includes bell-cranks 23 and link 88, and is located in the rear of the other linkages, Figure 8. The horizontally moving member 88 of this linkage has one operating pin 89 for every digit type-key, and the rock-shafts 14 of said keys have each an arm 90 extending up to engage the corresponding pin 89, so that when any key is depressed this special linkage is operated independently of the other keys. The function of this linkage is to restore the "9" pin for any denomination, concomitantly with the setting of any other digit pin in 95 said denomination. This special linkage has no use when addition is being performed. It is provided with a set of the combs 59, corresponding to the subtraction combs 38, and supported and guided in a similar manner, and capable of depressing the rear ends of the "9" pin restoring levers 60. These combs 59 are shiftable by the same bars 42 that shift the other combs, and they go with the subtraction set, so that when the subtraction set is out of use this special linkage 58, 23, 88, is also out of use and accomplishes nothing; but when subtraction combs are shifted into use, then the combs 59 of this linkage are also shifted into use, and hence 100 the "9" pins are automatically reset one at a time, in the selected denominations.

At Figure 6 the registers are all set for addition, but at Figures 5, 7 and 8 the left-hand register is set for subtraction. At the 115 operation of the digit type keys 10 to write a number in the desired column on the work-sheet, all of the dogs 31, 47 may operate upon corresponding jacks in the usual manner, so that pins 26 are set for all of the registers, those set in the left-hand register being complementary as compared with those set in the other two registers. Then the number so set up may be carried into the respective registers 29 by means of a power-driven general operator, such as set forth in said patents. There is illustrated in the present instance a manually-driven general operator, comprising a handle 91 which operates a general transverse shaft 92, the lat- 120 125 130

ter having segments 93 connected by idle pinions 94 to racks 95, one at each side of the machine and guided for forward movement. These racks are connected by a transverse 5 bar 96, forming therewith a general operator frame or carriage. The forward edge of the advancing bar 96 engages such pins as have been depressed, and drives forward their racks 28 corresponding distances, thereby running the numbers into all the registers 29. At the conclusion of its forward stroke, the transverse bar 96 engages lugs 97 on the subtraction bars 69, and returns them to normal positions against the tension of 10 spring 70; and the latches 71 are caused by the springs 75 to catch into the notches on said bar 69, to retain them in their forward positions, the subtraction keys 57 at the same time returning to normal positions. After 15 the completion of the forward stroke, the direction of the general operator handle 91 is reversed, and the carry-over mechanism (not shown) is operated, and the transverse bar 96 engages lugs 98 on the pin bars 65, 27 and restores them to normal positions. It 20 will be understood, however, that, at the conclusion of any subtraction operation, the general operator restores all the "9" pins which remain set, this being accomplished 25 by means of the table or platform 105. These pin-restoring devices may operate simultaneously for all of the registers, whether used for subtraction or addition.

As set forth in said Thornton Patent 35 1,283,360, the general operator performs several functions during both its advance and return strokes. One of its returning functions is to restore all of the set pins 26 to their normal raised positions, preparatory to 40 a subsequent computation. For this purpose, there is pivoted on the general operator a pawl 100, which, on the forward stroke of the operator, swings idly past an arm 101 fixed on a transverse rock-shaft 102. A 45 spring 103 snaps the pawl 100 back to normal position when it advances past said arm; and upon the return stroke of the general operator, said pawl 100 will act as a cam and swing the arm 101 upwardly, thereby rocking shaft 102 and also an arm 104 thereon, the latter engaging and raising a pin-restoring table or 50 plate 105 (of which there is one for each register) to raise all of the set pins 26. Each 55 of said pin-restoring plates is supported for parallel motion by means of two pairs of bell-crank levers 106, connected by links 107.

When it is desired for any register to be 60 set permanently to subtraction, for convenience where subtraction is to be performed in successive lines of typing, its subtraction key 57 may be pushed back, and then a finger-piece 108 may be lifted from the Figure 2 position, to swing a latch 109 down behind a pin 110 which is provided upon the subtraction bar 56, as at Figure 9. The register will

thus be maintained indefinitely in condition for subtraction.

Whether the subtraction key is latched back or not, provision is made whereby, when the subtraction bar 69 is carried forward by 70 the cross-bar 96 of the general operator, a pivoted latch 111 drops behind a pin 112 on said subtraction bar, to detain the latter in its forward position during the main portion of the return stroke of the general operator. At the conclusion of such return stroke, a pin 113, which is fixed on an arm 114 on the general rock-shaft 92, strikes a lug 115 which depends from said latch, and lifts it to free the pin 112, whereby the subtraction 75 bar is freed to be drawn back by the spring 70; this occurring just as the general operator is finishing its return stroke. This backward movement of the subtraction bar causes, among other things, all of the "9" pins to 80 be reset for that register, preparatory to the next computation. The latching and releasing operation just described is set forth in said Minton Patent 1,280,065. Hence the resetting of the "9" pins in the subtraction register 85 occurs automatically at the conclusion of each cycle of operation of the general operator, so long as the subtraction key 57 is latched in.

When it is desired to restore the register 90 to condition for addition, the key or finger-piece 108 may be depressed to lift the latch 109 and release the pin 110 and permit the spring 75 to return the subtraction key 57. At the same time it is required to restore 100 to normal position the "9" pins which, as just explained, were automatically set at the conclusion of the last cycle of the general operator. For this purpose the lifting of the latch-key 108 is caused to raise the pin-restoring plate 105, thereby to lift back the set "9" pins. To the rear end of the latch 109 is pivoted a vertical link 116, which, at its lower end moves in a fixed guide 117, and on this link is pivoted a hook 118 to lift the 105 forward end of a lever 119, which is pivoted at its rear end upon one of the rock-shafts 120 of the described linkage. On the down-stroke of the link 116, the hook 118 rides idly over the point of said lever 119, and is then 110 caused by a spring 121 to snap under the end of said lever. The hook maintains this position, Figure 9, as long as this register remains in subtraction condition. When, however, the latch-key 108 is depressed, the link 116 is 115 raised, together with the hook 118, thereby lifting the lever 119, the latter having an upward projection 122 which lifts the table 105 to restore the set "9" pins. Further upward movement of the link 116 will cause the hook 125 118 to be cammed away from the lever by means of a cam 123 formed on the top end of a hook arm to engage a pin 124 fixed upon the framework, the hook thus being normally out of use, as at Figure 2. 120

8
The setting of any subtraction key 57 also brings into use a device which provides for adding an extra unit in that register at the operation of the general operator, to produce an arithmetical complement. Mechanism of this character is disclosed in said patents, and is in common use on said Underwood machine.

Each of the registers may be provided with means for introducing an extra unit into the units dial wheel at the operation of subtracting by complementary addition. Such device, as seen at Figure 3, may correspond with that device disclosed in the Gumprecht Patent No. 1,285,134 (Figures 22 and 23 of said patent), in which a supernumerary bar 125 has a lateral lug 126 located one step in advance of the front edge of the cross-bar 96 of the general operator. This lug 126 is for the purpose of engaging whatever pin is set on the units bar 27, so as to give the units wheel 29 an extra step of rotation. Upon the supernumerary bar 125 is pivoted an arm 127, which is depressible by the same bail 61 which sets the "9" pins, said arm being depressed into the path of the general cross-bar 96 to enable the latter to advance the supernumerary bar, together with its lug 126 and the units bar 27, for the purpose specified. After the completion of the subtraction operation, this arm 127 is returned to normal condition by the usual pin-restoring table 105, thereby rendering the supernumerary bar 125 idle. The top of each non-rotatable index-pin 26 may be slightly cupped as at 128, Figure 1, and the tips of the comb-teeth may be correspondingly beveled to overcome any tendency of the comb-teeth to slip off from the pins.

40 Variations may be resorted to within the scope of the invention, and portions of the improvements may be used without others.

Having thus described my invention, I claim:

45 1. In a machine in which subtraction is performed by the method of complementary addition, the combination of a single register, an operating mechanism therefor having a system of indexing devices, a set of nine digit keys, denomination-selecting means, linkage mechanism controlled by the keys for setting the indexing devices selectively, each of the first eight keys provided with a double linkage comprising concurrently operable addition and subtraction parts, and shiftable means co-operative with said double linkages to cause one or the other of said parts to engage and set indexing devices for either addition or subtraction.

50 2. In a machine in which subtraction is performed by the method of complementary addition, the combination of a register mechanism having a system of indexing devices, a set of nine digit keys, denomination-select-

ing means, linkage mechanism controlled by the keys for setting the indexing devices selectively, said linkage mechanism including bars for setting indexing devices at the addition operation, and also including other bars for setting indexing devices at the subtraction operation, and means for rendering one set of bars effective and the other set ineffective.

55 3. In an adding machine having denomination-selecting means, the combination with a registering mechanism including a set of indexing devices, of a set of nine digit keys, and index-setting bars operable by said keys, each bar carrying means to set the indexing devices, said setting means being shiftable on said bar into and out of effective position, two of such bars being operable by each of the first eight keys, and one of the bars being complementary to the other for each of said eight keys.

60 4. In an adding and subtracting machine in which subtraction is performed by the method of complementary addition, the combination of a registering mechanism including a set of indexing devices, a set of nine digit keys, and linkage mechanism operable by the keys and including bars having devices mounted thereon for setting the indexing devices, each of the keys "1" to "8" capable of operating two of the bars, and the setting devices being shiftable into and out of effective positions relatively to said bars.

65 5. In an adding and subtracting machine in which subtraction is performed by the method of complementary addition, the combination of a registering mechanism including a set of indexing devices, a set of nine digit keys, linkage mechanism operable by the keys and including bars having combs mounted thereon for setting the indexing devices, each of the keys "1" to "8" capable of operating two of the bars, and the combs being shiftable into and out of effective positions relatively to said bars, and shiftable means for concomitantly shifting the subtraction combs into use and the addition combs out of use.

70 6. In an adding and subtracting machine in which subtraction is performed by the method of complementary addition, the combination of a registering mechanism including a set of indexing devices, a set of nine digit keys, linkage mechanism operable by the keys and including bars having combs mounted thereon for setting the indexing devices, each of the keys "1" to "8" capable of operating two of the bars, and the combs being shiftable into and out of effective positions relatively to said bars, and shiftable means to move the addition combs endwise to bring their teeth to positions where they may move down idly between the indexing devices and concomitantly shift the subtraction combs out of use.

tion combs endwise to positions where they may set the indexing devices.

7. In a machine in which subtraction is performed by the method of complementary addition, the combination of a registering mechanism having a system of indexing devices, digit keys, denomination-selecting means, rock-shafts operable by the keys, rock-arms upon the shafts, simultaneously operable addition and subtraction linkages appropriately connected to the rock-arms, whereby, upon the operation of a digit key, both an addition linkage and a subtraction linkage may be operated, and shiftable devices connected to said linkages to enable either the addition linkages or the subtraction linkages to be effective. 10
8. In a machine in which subtraction is performed by the method of complementary addition, the combination of a single register, an operating mechanism therefor having a system of indexing devices, a set of nine digit keys, denomination-selecting means, rock-shafts operable by the keys, rock-arms upon the shafts, simultaneously-operable addition and subtraction linkages appropriately connected to the rock-arms, whereby, upon the operation of any of the first eight digit keys, both an addition linkage and a subtraction linkage may be operated, the rock-shaft for the digit key "9" having only an addition arm, a subtraction key having means to shift the connections between the keys and the indexing devices, and also having means to set the "9" indexing devices, and means for restoring any "9" indexing device when any other indexing device is set in the same denomination. 20
9. In a machine in which subtraction is performed by the method of complementary addition, the combination of a registering mechanism having a system of indexing devices, digit keys, denomination-selecting means, rock-shafts operable by the keys, rock-arms upon the shafts, simultaneously-operable addition and subtraction linkages appropriately connected to the rock-arms, whereby, upon the operation of a digit key, both an additional linkage and a subtraction linkage may be operated, each of said linkages including a link or bar which moves vertically at the stroke of its key, and devices shiftable upon said links or bars into and out of position for setting the indexing devices. 30
10. In a machine in which subtraction is performed by the method of complementary addition, the combination of a registering mechanism having a system of indexing devices, digit keys, denomination-selecting means, rock-shafts operable by the keys, rock-arms upon the shafts, simultaneously-operable addition and subtraction linkages appropriately connected to the rock-arms, whereby, upon the operation of a digit key, 40
- both an addition linkage and a subtraction linkage may be operated, each of said linkages including a link or bar which moves vertically at the stroke of its key, devices shiftable upon said links or bars into and out of position for setting the indexing devices, and a shifter bar connected to all of said shiftable devices, for shifting them simultaneously to shift one set of setting devices into use and the other set of setting devices out of use. 50
11. In a machine in which subtraction is performed by the method of complementary addition, the combination of a registering mechanism, having a system of indexing devices, digit keys, denomination-selecting means, rock-shafts operable by the keys, rock-arms upon the shafts, simultaneously-operable addition and subtraction linkages appropriately connected to the rock-arms, whereby, upon the operation of a digit key, both an addition linkage and a subtraction linkage may be operated, each of said linkages including a link or bar which moves vertically at the stroke of its key, and devices shiftable upon said links or bars into and out of position for setting the indexing devices, said shiftable devices in the nature of combs having teeth for setting the indexing devices, the teeth in the addition combs being opposite the spaces in the subtraction combs, all of said combs being connected so that when one set of combs is in use, the other set of combs is out of use. 60
12. In a machine in which subtraction is performed by the method of complementary addition, a registering mechanism comprising a set of indexing devices, nine digit keys, addition bars and subtraction bars for co-operating with the keys to set the indexing devices, each of the first eight keys being connected to operate an addition bar and a subtraction bar simultaneously, and shiftable means connected to all the bars to cause either the addition bars or the subtraction bars to be effective with relation to said indexing devices. 70
13. In a machine in which subtraction is performed by the method of complementary addition, a registering mechanism comprising a set of indexing devices, nine digit keys, addition bars and subtraction bars co-operating with the keys to set the indexing devices, each of the first eight keys being connected to operate an addition bar and a subtraction bar simultaneously, each of said bars provided with a displaceable comb for setting the indexing devices, and a shiftable member to which all of the combs are connected to be controlled thereby. 80
14. In a machine in which subtraction is performed by the method of complementary addition, a registering mechanism comprising a set of indexing devices, nine digit keys, addition bars and subtraction bars for 90
- 100
- 110
- 120
- 130

co-operating with the keys to set the indexing devices, each of the first eight keys being connected to operate an addition bar and a subtraction bar simultaneously, each 5 of said bars provided with a displaceable comb for setting the indexing devices, and a shiftable member to which all of the combs are connected to be controlled thereby, one series of said combs having only addition 10 teeth and the other series having only subtraction teeth, and the combs being shiftable endwise to bring either series into position over the indexing devices and the other series to position where the teeth will pass 15 idly between the indexing devices at the key operations.

15. In a machine in which subtraction is performed by the method of complementary addition, a registering mechanism comprising 20 a set of indexing devices, nine digit keys, addition bars and subtraction bars for co-operating with the keys to set the indexing devices, each of the first eight keys being connected to operate an addition bar 25 and a subtraction bar simultaneously, each of said bars provided with a displaceable comb for setting the indexing devices, each comb comprising a strip having pendent evenly-spaced teeth agreeing with the trans- 30 verse spacing of the indexing devices, and a shiftable member to which all of the combs are connected to be controlled thereby.

16. In a machine in which subtraction is performed by the method of complementary addition, the combination of a registering mechanism comprising a set of indexing devices, a set of nine digit keys, a set of addition bars, and a set of subtraction bars for 35 setting said indexing devices, each of the first eight digit keys being connected to operate an addition bar and a subtraction bar, each of said bars having slots, combs shiftable endwise in said slots and movable up and down by the bars, and having teeth to 40 set the indexing devices, and means to shift one set of combs into use and the other set out of use.

17. In a machine in which subtraction is performed by the method of complementary addition, the combination of a registering mechanism comprising a set of indexing devices, a set of nine digit keys, a set of addition bars, and a set of subtraction bars for 45 setting said indexing devices, each of the first eight digit keys being connected to operate an addition bar and a subtraction bar, each of said bars having slots, combs shiftable endwise in said slots and movable up and down by the bars, and having teeth to 50 set the indexing devices, and means to shift one set of combs into use and the other set out of use, said slots extending longitudinally of the bars, said combs having ears working in said slots, and said slots being 55 open at the bottom, the comb teeth project-

ing below the bars, and said slots being of sufficient length to permit the shifting of the combs.

18. In a machine in which subtraction is performed by the method of complementary addition, the combination of a registering mechanism comprising a set of indexing devices, a set of nine digit keys, a set of addition bars, and a set of subtraction bars for 60 setting said indexing devices, each of the first eight digit keys being connected to operate an addition bar and a subtraction bar, each of said bars having slots, combs shiftable endwise in said slots and movable up and down by the bars, and having teeth to 65 set the indexing devices, the subtraction combs having teeth opposite the spaces between the teeth on the addition combs, and all of the combs having aligned slots and a shifter bar extending through the slots to 70 shift the combs endwise, said aligned slots being extended vertically to permit the movements of the combs when setting the indexing devices.

19. In a machine in which subtraction is performed by the method of complementary addition, the combination of a registering mechanism comprising a set of indexing devices, a set of nine digit keys, a set of addition bars, and a set of subtraction bars for 75 setting said indexing devices, each of the first eight digit keys being connected to operate an addition bar and a subtraction bar, each of said bars having slots, combs shiftable endwise in said slots and movable up 80 and down by the bars, and having teeth to set the indexing devices, the subtraction combs having teeth opposite the spaces between the teeth on the addition combs, and all of the combs having aligned slots and a shifter bar extending through the slots to 85 shift the combs endwise, said aligned slots being extended vertically to permit the movements of the combs when setting the indexing devices.

19. In a machine in which subtraction is performed by the method of complementary addition, the combination of a registering mechanism comprising a set of indexing devices, a set of nine digit keys, a set of addition bars, and a set of subtraction bars for 90 setting said indexing devices, each of the first eight digit keys being connected to operate an addition bar and a subtraction bar, each of said bars having slots, combs shiftable endwise in said slots and movable up 95 and down by the bars, and having teeth to set the indexing devices, the subtraction combs having teeth opposite the spaces between the teeth on the addition combs, and all of the combs having aligned slots and a shifter bar extending through the slots to 100 shift the combs endwise, said aligned slots being extended vertically to permit the movements of the combs when setting the indexing devices, a rock-shaft connected to 105 said shifter bar to operate the same, and means at the keyboard to operate the rock-shaft and concomitantly set other portions 110 of the registering mechanism to subtraction condition.

20. In a machine in which subtraction is performed by the method of complementary addition, the combination of a registering mechanism comprising a set of indexing devices, a set of nine digit keys, a set of addition bars, and a set of subtraction bars for 115 setting said indexing devices, each of the first eight digit keys being connected to operate an addition bar and a subtraction bar, each of said bars having slots, combs shiftable endwise in said slots and movable up 120 and down by the bars, and having teeth to set the indexing devices, means to shift one set of combs into use and the other set out of use, each comb having about the 125

same thickness as the bar in which it is mounted, and guides common to the bars and combs to guide the same vertically.

21. In a machine in which subtraction is performed by the method of complementary addition, the combination of a registering mechanism comprising a set of indexing devices, a set of nine digit keys, a set of addition bars, and a set of subtraction bars for setting said indexing devices, each of the first eight digit keys being connected to operate an addition bar and a subtraction bar, each of said bars having slots, combs shiftable endwise in said slots and movable up and down by the bars, and having teeth to set the indexing devices, means to shift one set of combs into use and the other set out of use, each comb having about the same thickness as the bar in which it is mounted, and guides common to the bars and combs to guide the same vertically, said guides including a series of plates arranged on edge and extending from front to back adjacent to the registering mechanism and having guide-slots for the bars and combs, two bars with their combs working in each slot, the bars with their combs being placed closely face to face, so that any appropriate indexing device may be reached by either comb, said bars being thus guided in pairs, and each of the first eight digit keys being connected to operate an addition bar in one pair and a subtraction bar in another pair.

22. In a machine in which subtraction is performed by the method of complementary addition, the combination of a registering mechanism comprising a set of indexing devices, a set of nine digit keys, a set of addition bars, and a set of subtraction bars for setting said indexing devices, each of the first eight digit keys being connected to operate an addition bar and a subtraction bar, each of said bars having slots, combs shiftable endwise in said slots and movable up and down by the bars, and having teeth to set the indexing devices, means to shift one set of combs into use and the other set out of use, each comb having about the same thickness as the bar in which it is mounted, and guides common to the bars and combs to guide the same vertically, said guides including a series of plates arranged on edge and extending from front to back adjacent to the registering mechanism and having guide-slots for the bars and combs.

23. In a machine in which subtraction is performed by the method of complementary addition, the combination of a registering mechanism comprising a set of indexing devices, a set of nine digit keys, a set of addition bars, and a set of subtraction bars for setting said indexing devices, each of said bars having slots, combs shiftable endwise in said slots and movable up and down by the bars, and having teeth to set the indexing devices, means to shift one set of combs into use and the other set out of use, each comb having about the same thickness as the bar in which it is mounted, and guides common to the bars and combs to guide the same vertically, said guides including a series of plates arranged on edge and extending from front to back adjacent to the registering mechanism and having guide-slots for the bars and combs, two bars with their combs working in each slot, the bars with their combs being placed closely face to face, so that any appropriate indexing device may be reached by either comb.

24. In a machine in which subtraction is performed by the method of complementary addition, the combination of a registering mechanism comprising a set of indexing devices, a set of nine digit keys, a set of addition bars, and a set of subtraction bars for setting said indexing devices, each of the first eight digit keys being connected to operate an addition bar and a subtraction bar, each of said bars having slots, combs shiftable endwise in said slots and movable up and down by the bars, and having teeth to set the indexing devices, a subtraction shift-key, a bar shiftable thereby, an arm to which said bar is connected, a rock-shaft carrying said arm, a second arm upon said rock-shaft, a link connecting the second arm, a second rock-shaft having an arm connected to said link, and a bar connected to the second rock-shaft and extending through slots in all of said combs to shift the addition combs to ineffective positions and the subtraction combs to effective positions.

25. In a machine in which subtraction is performed by the method of complementary addition, the combination of a registering mechanism comprising a set of indexing devices, a set of nine digit keys, a set of addition bars, and a set of subtraction bars for setting said indexing devices, each of the first eight digit keys being connected to operate an addition bar and a subtraction bar, each of said bars having slots, combs shiftable endwise in said slots and movable up and down by the bars, and having teeth to set the indexing devices, a subtraction shift-key, a bar connected to the subtraction shift-key and extending through slots in all of said combs to shift the addition combs to ineffective positions and the subtraction combs to effective positions, means connected to said subtraction key to set all the "9" indexing devices and to control the automatic insertion of an extra "1" in the units place in the register, and means operable by any of the first eight digit keys for restoring the set "9" indexing device in any denomination.

26. In a machine in which subtraction is performed by the method of complementary addition, the combination of a registering mechanism comprising a set of indexing de-

- vices, a set of nine digit keys, a set of addition bars, and a set of subtraction bars for setting said indexing devices, each of the first eight digit keys being connected to operate an addition bar and a subtraction bar, each of said bars having slots, combs shiftable endwise in said slots and movable up and down by the bars, and having teeth to set the indexing devices, a subtraction shift key, a bar connected to the subtraction shift key and extending through slots in all of said combs to shift the addition combs to ineffective positions and the subtraction combs to effective positions, means connected to said subtraction key to set all the "9" indexing devices and to control the automatic insertion of an extra "1" in the units place in the register, a bar operable by any of the first eight digit keys, and means shiftable into and out of use upon the last-mentioned bar for enabling the same to restore any of the set "9" indexing devices.
27. In a machine in which subtraction is performed by the method of complementary addition, the combination of a registering mechanism comprising a set of indexing devices, a set of nine digit keys, a set of addition bars, and a set of subtraction bars for setting said indexing devices, each of the first eight digit keys being connected to operate an addition bar and a subtraction bar, each of said bars having slots, combs shiftable endwise in said slots and movable up and down by the bars, and having teeth to set the indexing devices, a subtraction shift key, a bar connected to the subtraction shift key and extending through slots in all of said combs to shift the addition combs to ineffective positions and the subtraction combs to effective positions, means connected to said subtraction key to set all the "9" indexing devices and to control the automatic insertion of an extra "1" in the units place in the register, a bar operable by any of the first eight digit keys, and combs upon said last-mentioned bar and connected to shift into use simultaneously with the subtraction combs, and capable of restoring any of the set "9" indexing devices.
28. In a machine for subtracting by the complementary addition method, a registering mechanism including a set of indexing devices, a set of digit keys, a subtraction key, means controlled by said subtraction key for setting all the "9" indexing devices, a bar operable by the first eight digit keys, a setter controlled by said subtraction key to be adjusted on said bar into and out of use, and devices operable by said setter for restoring any previously set "9" indexing device.
29. In an adding and subtracting machine in which subtraction is performed by the method of complementary addition, the combination of registers, each having a system of indexing devices, a set of digit keys, denomination-selecting means, means controlled by the keys for setting indexing devices in said registers simultaneously, each key provided with a double linkage, and means shiftable on said linkages for enabling each digit key to set in all of said registers either a corresponding indexing device for addition or a complementary indexing device for subtraction.
30. In an adding and subtracting machine in which subtraction is performed by the method of complementary addition, the combination of registers, each having a system of indexing devices, a set of digit keys, denomination-selecting means, means controlled by the keys for setting indexing devices in said registers simultaneously, each key provided with a double linkage, means shiftable on said linkages for enabling each digit key to set in all of said registers either a corresponding indexing device for addition or a complementary indexing device for subtraction, said linkages including bars common to the registers for setting indexing devices at the addition operation and other bars also common to the registers for setting indexing devices at the subtraction operation, and means for rendering one set of bars effective and the other set ineffective.
31. In an adding machine, the combination with a plurality of registers, each including a set of indexing devices, of digit keys, bars operable by said keys, each bar carrying combs having teeth to set the indexing devices, each comb being shiftable on said bar into and out of effective position, and complementary bars operable by the same keys and each having setting combs shiftable into and out of effective positions.
32. In a machine in which subtraction is performed by the method of complementary addition, the combination of a plurality of registers, each including a set of indexing devices, digit keys, and linkage mechanism operable by the keys and common to the registers and including bars having devices extending longitudinally thereof for setting indexing devices in a plurality of registers simultaneously, each of the keys "1" to "8" capable of operating complementary bars, of which one is complementary of the other, and the setting devices being shiftable for all the registers, to shift the setting devices for subtraction into use and the devices for addition out of use.
33. In a machine in which subtraction is performed by the method of complementary addition, the combination of a plurality of registers, each including a set of indexing devices, digit keys, linkage mechanism operable by the keys and common to the registers and including bars having combs ex-

- tending longitudinally thereof for setting indexing devices in a plurality of registers simultaneously, each of the keys "1" to "8" capable of operating complementary bars, of which one is complementary of the other, and the setting combs being shiftable for all the registers, and means to move the teeth of the addition combs to positions where they may move down idly between the indexing devices and simultaneously shift the subtraction combs to positions where they may reach the indexing devices to set the same.
34. In a machine in which subtraction is performed by the method of complementary addition, the combination of a plurality of registers, each including a set of indexing devices, digit keys, linkage mechanism operable by the keys and common to the registers and including bars having combs extending longitudinally thereof for setting indexing devices in a plurality of registers simultaneously, each of the keys "1" to "8" capable of operating complementary bars, of which one is complementary of the other, and the setting combs being shiftable for all the registers, and means to move the teeth of the addition combs to positions where they may move down idly between the indexing devices and simultaneously shift the subtraction combs to positions where they may reach the indexing devices to set the same, a plurality of shifters being employed, one for shifting all of the combs for each register.
35. In a machine in which subtraction is performed by the method of complementary addition, the combination of a plurality of registers, each having a system of indexing devices, digit keys, denomination-selecting means, rock-shafts operable by the keys, rock-arms upon the shafts, simultaneously-operable addition and subtraction linkages connected to the appropriate rock-arms, whereby, upon the operation of a digit key, both an addition linkage and a subtraction linkage may be operated, said linkages common to the registers, and shiftable means connected to said linkages to enable either the addition linkages or the subtraction linkages to be effective for any selected register.
36. In a machine in which subtraction is performed by the method of complementary addition, the combination of a plurality of registers, each having a system of indexing devices, digit keys, denomination-selecting means, rock-shafts operable by the keys, rock-arms upon the shafts, simultaneously-operable addition and subtraction linkages connected to the appropriate rock-arms, whereby, upon the operation of a digit key, both an addition linkage and a subtraction linkage may be operated, said linkages common to the registers, shiftable means connected to said linkages to enable either the addition linkages or the subtraction linkages to be effective for any selected register.
37. In a machine in which subtraction is performed by the method of complementary addition, the combination of a plurality of registers, each having a system of indexing devices, digit keys, denomination-selecting means, rock-shafts operable by the keys, rock-arms upon the shafts, simultaneously-operable addition and subtraction linkages connected to the appropriate rock-arms, whereby, upon the operation of a digit key, both an addition linkage and a subtraction linkage may be operated, said linkages common to the registers, shiftable means connected to said linkages to enable either the addition linkages or the subtraction linkages to be effective for any selected register, the rock-shaft for the digit key "9" having only an addition arm, a subtraction key for each register, each subtraction key having means to shift the connections between the digit keys and the indexing devices, and also having means to set the "9" indexing devices, and means operable by digit keys for restoring any "9" indexing device when another indexing device is set in the same denomination.
38. In a machine in which subtraction is performed by the method of complementary addition, the combination of a plurality of registers, each having a system of indexing devices, digit keys, denomination-selecting means, rock-shafts operable by the keys, rock-arms upon the shafts, simultaneously-operable addition and subtraction linkages connected to the appropriate rock-arms, whereby, upon the operation of a digit key, both an addition linkage and a subtraction linkage may be operated, said linkages common to the registers, shiftable means connected to said linkages to enable either the addition linkages or the subtraction linkages to be effective for any selected register, the rock-shaft for the digit key "9" having only an addition arm, a subtraction key for each register, each subtraction key having means to shift the connections between the digit keys and the indexing devices, and also having means to set the "9" indexing devices, means operable by digit keys for restoring any "9" indexing device when another indexing device is set in the same denomination.

ing device when another indexing device is set in the same denomination for the same register, each of said linkages including a bar which moves vertically at the stroke of its key, sets of devices for the different registers, each set shiftable upon said bars into and out of position for setting indexing devices for its register, and shifter bars connected to said sets of shiftable devices for shifting all the devices in each set simultaneously.

39. In a machine in which subtraction is performed by the method of complementary addition, the combination of a plurality of registers, each having a system of indexing devices, digit keys, denomination-selecting means, rock-shafts operable by the keys, rock-arms upon the shafts, simultaneously-operable addition and subtraction linkages connected to the appropriate rock-arms, whereby, upon the operation of a digit key, both an addition linkage and a subtraction linkage may be operated, said linkages common to the registers, shiftable means connected to said linkages to enable either the addition linkages or the subtraction linkages to be effective for any selected register, the rock-shaft for the digit key "9" having only an addition arm, a subtraction key for each register, each subtraction key having means to shift the connections between the digit keys and the indexing devices, and also having means to set the "9" indexing devices, means operable by digit keys for restoring any "9" indexing device when another indexing device is set in the same denomination for the same register, each of said linkages including a bar which moves vertically at the stroke of its key, sets of devices for the different registers, each set shiftable upon said bars into and out of position for setting indexing devices for its register, and shifter bars connected to said sets of shiftable devices for shifting all the devices in each set simultaneously, the shiftable devices in each set being in the nature of combs having teeth for setting the indexing devices, the teeth in the addition combs being opposite the spaces in the subtraction combs for each register, so that when one set of combs is in use for any register the other set of combs for the same register is out of use.

40. In a machine in which subtraction is performed by the method of complementary addition, a plurality of registers, each comprising a set of indexing devices, nine digit keys, addition bars and subtraction bars common to the registers for co-operating with the keys to set indexing devices for any register, each of the first eight keys being connected to operate an addition bar and a subtraction bar simultaneously, and a shifter at each register and connected to all

the bars to change them from addition to subtraction condition for that register.

41. In a machine in which subtraction is performed by the method of complementary addition, a plurality of registers, each comprising a set of indexing devices, nine digit keys, addition bars and subtraction bars common to the registers for co-operating with the keys to set indexing devices for any register, each of the first eight keys being connected to operate an addition bar and a subtraction bar simultaneously, and a shifter at each register and connected to all the bars to change them from addition to subtraction condition for that register, each of said bars provided with a plurality of displaceable combs for setting the indexing devices for the different registers, and all of the combs for each register being connected to a single shifter to be controlled thereby, the shifters being individual to the registers.

42. In a machine in which subtraction is performed by the method of complementary addition, a plurality of registers, each comprising a set of indexing devices, nine digit keys, addition bars and subtraction bars common to the registers for co-operating with the keys to set indexing devices for any register, each of the first eight keys being connected to operate an addition bar and a subtraction bar simultaneously, and a shifter at each register and connected to all the bars to change them from addition to subtraction condition for that register, each of said bars provided with a plurality of displaceable combs for setting the indexing devices for the different registers, and all of the combs for each register being connected to a single shifter to be controlled thereby, the shifters being individual to the registers, one series of said combs having only addition teeth and the other series having only subtraction teeth, and the combs for each register being shiftable endwise independently of the other registers to bring either series of combs into position over the indexing devices for that register, and the other series to position where the teeth will pass idly between the indexing devices at the key operations.

43. In a machine in which subtraction is performed by the method of complementary addition, a plurality of registers, each comprising a set of indexing devices, nine digit keys, addition bars and subtraction bars common to the registers for co-operating with the keys to set indexing devices for any register, each of the first eight keys being connected to operate an addition bar and a subtraction bar simultaneously, and a shifter at each register and connected to all the bars to change them from addition to subtraction condition for that register, each

- of said bars provided with a plurality of bars for that register shall add or subtract 65
 displaceable combs for setting the indexing devices for the different registers, and all of the combs for each register being connected
 5 to a single shifter to be controlled thereby, the shifters being individual to the registers, one series of said combs having only addition teeth and the other series having only subtraction teeth, and the combs for
 10 each register being shiftable endwise independently of the other registers to bring either series of combs into position over the indexing devices for that register, and the other series to position where the teeth will
 15 pass idly between the indexing devices at the key operations, the combs on each bar arranged end to end and each comb comprising a strip having pendent evenly-spaced teeth agreeing with the transverse spacing
 20 of the indexing devices.
44. In a machine in which subtraction is performed by the method of complementary addition, said machine comprising a plurality of registers, each comprising a set of indexing devices, digit keys for all of the registers, bars common to the registers and operable by the digit keys for setting the indexing devices, denomination-determining mechanism, said bars including addition
 25 bars and subtraction bars, each of the first eight digit keys capable of operating both an addition bar and a subtraction bar, and shifters to render the subtraction bars for one register effective or ineffective independently of another register.
45. In a machine in which subtraction is performed by the method of complementary addition, said machine comprising a plurality of registers, each comprising a set of indexing devices, digit keys for all of the registers, bars common to the registers and operable by the digit keys for setting the indexing devices, denomination-determining mechanism, and shiftable means individual
 40 to each register for determining independently of the other registers whether the bars for that register shall add or subtract at the operation of the keys, each of said bars carrying a plurality of combs for setting
 45 indexing devices in the various registers, and the combs for one register being settable independently of the other registers to either addition or subtraction condition.
46. In a machine in which subtraction is performed by the method of complementary addition, said machine comprising a plurality of registers, each comprising a set of indexing devices, digit keys for all of the registers, bars common to the register and
 50 operable by the digit keys for setting the indexing devices, denomination-determining mechanism, and shiftable means individual to each register for determining independently of the other registers whether the
 55 bars for that register shall add or subtract at the operation of the keys, each of said bars carrying a plurality of combs for setting
 60 indexing devices in the various registers, and the combs for one register being settable independently of the other registers to either addition or subtraction condition.
47. In a machine in which subtraction is performed by the method of complementary addition, the combination with a plurality of registers each comprising a set of indexing devices, of digit keys, a set of addition bars and a set of subtraction bars for setting said indexing devices, each of the first eight digit keys being connected to operate both an addition bar and a subtraction bar, each of said bars having slots, combs shiftable endwise in said slots and movable up and down by the bars, and having teeth to set the indexing devices, and shifters individual to the registers, each shifter connected to shift one set of combs for that register into use and the other set out of use.
48. In a machine in which subtraction is performed by the method of complementary addition, the combination with a plurality of registers each comprising a set of indexing devices, of digit keys, a set of addition bars and a set of subtraction bars for setting said indexing devices, each of the first eight digit keys being connected to operate both an addition bar and a subtraction bar, each of said bars having slots, combs shiftable endwise in said slots and movable up and down by the bars, and having teeth to set the indexing devices, and shifters individual to the registers, each shifter connected to shift one set of combs for that register into use and the other set out of use, each of said bars having a series of extended longitudinal slots in which the combs are shifted, said combs having ears working in said slots, said slots open at the bottom, and the comb teeth projecting from the open slots.
49. In a machine in which subtraction is performed by the method of complementary addition, the combination with a plurality of registers each comprising a set of indexing devices, of digit keys, a set of addition bars and a set of subtraction bars for setting said indexing devices, each of the first eight digit keys being connected to operate both an addition bar and a subtraction bar, each of said bars having slots, combs shiftable endwise in said slots and movable up and down by the bars, and having teeth to set the indexing devices, and shifters individual to the registers, each shifter connected to

shift one set of combs for that register into use and the other set out of use, each of said bars having a series of extended longitudinal slots in which the combs are shifted, said combs having ears working in said slots, said slots open at the bottom, and the comb teeth projecting from the open slots, the subtraction combs for each register having teeth opposite the spaces between the teeth 10 on the addition combs for that register, and all of the combs for each register having aligned slots, said shifters comprising bars individual to the registers and extending through the slots to shift the combs endwise, 15 said slots being extended vertically to permit the vertical movements of the combs when setting the indexing devices.

50. In a machine in which subtraction is performed by the method of complementary addition, the combination with a plurality of registers each comprising a set of indexing devices, of digit keys, a set of addition bars and a set of subtraction bars for setting said indexing devices, each of the first eight 25 digit keys being connected to operate both an addition bar and a subtraction bar, each of said bars having slots, combs shiftable endwise in said slots and movable up and down by the bars, and having teeth to set the 30 indexing devices, shifters individual to the registers, each shifter connected to shift one set of combs for that register into use and the other set out of use, each of said bars having a series of extended longitudinal 35 slots in which the combs are shifted, said combs having ears working in said slots, said slots open at the bottom, and the comb teeth projecting from the open slots, each comb having about the same thickness as the bar in which it is mounted, and guides 40 at the various registers engaging the bars and combs to guide the same vertically.

51. In a machine in which subtraction is performed by the method of complementary addition, the combination with a plurality of registers each comprising a set of indexing devices, of digit keys, a set of addition bars and a set of subtraction bars for setting said indexing devices, each of the first 45 eight digit keys being connected to operate both an addition bar and a subtraction bar, each of said bars having slots, combs shiftable endwise in said slots and movable up and down by the bars, and having teeth to 50 set the indexing devices, shifters individual to the registers, each shifter connected to shift one set of combs for that register into use and the other set out of use, each of said bars having a series of extended longitudinal 55 slots in which the combs are shifted, said combs having ears working in said slots, said slots open at the bottom, and the comb teeth projecting from the open slots, each comb having about the same thickness as the bar in which it is mounted, and guides 60

at the various registers engaging the bars and combs to guide the same vertically, said guides including guide plates at the different registers, arranged on edge and extending from front to back and having guide 70 slots for the bars and combs, two bars with their combs working in each slot face to face, so that any indexing device in any set may be reached by either appropriate comb.

52. In a machine in which subtraction is performed by the method of complementary addition, the combination with a plurality of registers each comprising a set of indexing devices, of digit keys, a set of addition bars and a set of subtraction bars for setting 75 said indexing devices, each of said bars having slots, combs shiftable endwise in said slots and movable up and down by the bars, and having teeth to set the indexing devices, shifters individual to the registers, each 80 shifter connected to shift one set of combs for that register into use and the other set out of use, each of said bars having a series of extended longitudinal slots in which the combs are shifted, said combs having ears 85 working in said slots, said slots open at the bottom, and the comb teeth projecting from the open slots, each comb having about the same thickness as the bar in which it is mounted, and guides at the various registers 90 engaging the bars and combs to guide the same vertically, said guides including guide plates at the different registers, arranged on edge and extending from front to back and having guide slots for the bars and combs, two bars with their combs working in each 95 slot face to face, so that any indexing device in any set may be reached by either appropriate comb, said bars being thus arranged in pairs, and each of the first eight 100 digit keys being connected to operate an addition bar in one pair and a subtraction bar in another pair.

53. In a machine in which subtraction is performed by the method of complementary 110 addition, the combination with a plurality of registers each comprising a set of indexing devices, of digit keys, a set of addition bars and a set of subtraction bars for setting said indexing devices, each of the first eight 115 digit keys being connected to operate both an addition bar and a subtraction bar, each of said bars having slots, combs shiftable endwise in said slots and movable up and down by the bars, and having teeth to set the 120 indexing devices, a subtraction shift key for each register, a bar shiftable thereby, an arm to which said bar is connected, a rock-shaft carrying said arm, a second arm upon said rock-shaft, a link connecting the second arm, a second rock-shaft having an arm 125 connected to said link, and a bar connected to the second rock-shaft and extending through slots in all of said combs for that register, to shift the addition combs to inef- 130

fective positions and the subtraction combs to effective positions independently of the remaining registers.

54. In a machine in which subtraction is performed by the method of complementary addition, the combination with a plurality of registers each comprising a set of indexing devices, of digit keys, a set of addition bars and a set of subtraction bars for setting said indexing devices, each of the first eight digit keys being connected to operate both an addition bar and a subtraction bar, each of said bars having slots, combs shiftable endwise in said slots and movable up and down by the bars, and having teeth to set the indexing devices, a subtraction shift key for each register, a bar connected to the subtraction shift key and extending through slots in all of said combs for that register, to shift the addition combs to ineffective positions and the subtraction combs to effective positions independently of the remaining registers, means connected to each subtraction shift key to set all the "9" indexing devices in that register and to control the automatic insertion of an extra "1" in the units place in that register, independently of the other registers, and means operable by any of the first eight digit keys for restoring the set "9" indexing device in any denomination in any register.

55. In a machine in which subtraction is performed by the method of complementary addition, the combination with a plurality of registers each comprising a set of indexing devices, of digit keys, a set of addition bars and a set of subtraction bars for setting said indexing devices, each of the first eight digit keys being connected to operate both an addition bar and a subtraction bar, each of said bars having slots, combs shiftable endwise in said slots and movable up and down by the bars, and having teeth to set the indexing devices, a subtraction shift key for each register, a bar connected to the subtraction shift key and extending through slots in all of said combs for that register, to shift the addition combs to ineffective positions and the subtraction combs to effective positions independently of the remaining registers, means connected to each subtraction shift key to set all the "9" indexing devices in that register and to control the automatic insertion of an extra "1" in the units place in that register, independently of the other registers, a bar operable by any of the first eight digit keys, means shiftable into and out of use upon said bar for enabling the same to restore any of the set "9" indexing devices, and combs upon said bar and shiftable into use simultaneously with the subtraction combs for the same register and capable of restoring any of the set "9" indexing devices.

56. In a machine for subtracting by the

complementary addition method, a plurality of registers each including a series of indexing devices, a set of digit keys, a subtraction key for each register, means controlled by each subtraction key for setting all of the "9" indexing devices for that register, a bar operable by the first eight digit keys, combs individually adjustable on said bar into and out of use, and devices operable by each of said combs for restoring any previously set "9" indexing device for that register.

57. In an adding and subtracting machine in which subtraction is performed by the method of complementary addition, the combination with a series of registering mechanisms having individually operable subtraction keys whereby any registering mechanism may be set to subtraction independently of the other registering mechanisms, of indexing devices for each registering mechanism, a set of digit keys, means controlled by said subtraction keys for enabling the digit keys to set the indexing devices for either addition or subtraction, said machine including a general operator, means for latching any subtraction key in its operative position, and means to enable the general operator to reset automatically the "9" indexing devices in the same register and insert an extra "1" in the units place in said register independently of the other registers.

58. In an adding and subtracting machine in which subtraction is performed by the method of complementary addition, the combination with a series of registering mechanisms having individually operable subtraction keys whereby any registering mechanism may be set to subtraction independently of the other registering mechanisms, of indexing devices for each registering mechanism, a set of digit keys, means controlled by said subtraction keys for enabling the digit keys to set the indexing devices for either addition or subtraction, said machine including a general operator, means for latching any subtraction key in its operative position, means to enable the general operator to reset automatically the "9" indexing devices in the same register and insert an extra "1" in the units place in said register independently of the other registers, means connected to each of said latching means to release the same, and means also connected to said releasing means for restoring the set "9" indexing devices to normal positions for that register.

59. In a machine in which subtraction is performed by the method of complementary addition, the combination of a plurality of registers having each a system of indexing devices, a set of digit keys, denomination-selecting means, means controlled by the keys for setting indexing devices for a plurality of registers simultaneously, each key pro-

vided with a double linkage, and means shiftable on said linkages for enabling digit keys to set an indexing device for addition in one register and simultaneously set complementary indexing devices for subtraction in another register.

60. In a machine in which subtraction is performed by the method of complementary addition, the combination of a plurality of registers having each a system of indexing-devices, a set of digit keys, denomination-selecting means, means controlled by the keys for setting indexing devices for a plurality of registers simultaneously, each key provided with a double linkage, means shiftable on said linkages for enabling digit keys to set an indexing device for addition in one register and simultaneously set complementary indexing devices for subtraction in another register, said linkages including bars for setting indexing devices at the addition operation and other bars for setting indexing devices at the subtraction operation, and means individually shiftable for each register, for rendering one set of bars effective and the other set ineffective for that register.

61. In a machine in which subtraction is performed by the method of complementary addition, the combination of a plurality of registers, each including a set of indexing devices, digit keys, and linkage mechanism common to the registers and operable by the keys and including bars each having combs extending longitudinally thereof for setting the indexing devices for the different registers, each of the keys "1" to "8" capable of operating two of the bars, and the combs being endwise shiftable to bring the subtraction combs for either register into use while the addition combs for the other register are also in use.

62. In a machine in which subtraction is performed by the method of complementary addition, the combination of a plurality of registers, each having a system of indexing devices, digit keys, denomination-selecting means for the different registers, rock-shafts operable by the keys, arms upon the shafts, simultaneously-operable addition and subtraction linkages common to the registers and connected to the appropriate rock-arms, whereby, upon the operation of a digit key, both an addition linkage and a subtraction linkage may be operated for all the registers, and shiftable means individual to the registers and connected to said linkages, to enable the addition linkages to be effective for one register while the subtraction linkages are effective for another register.

63. In a machine in which subtraction is performed by the method of complementary addition, said machine comprising a plurality of registers, each comprising a set of

indexing devices, a set of digit keys for all of the registers, bars common to all the registers and operable by the digit keys for setting the indexing devices, denomination-determining mechanism, and means, including devices shiftable on the bars, for causing the bars to set indexing devices for subtraction for one register at the operation of the keys while the bars set indexing devices for addition for one or more other registers.

64. In a machine in which subtraction is performed by the method of complementary addition, said machine comprising a plurality of registers, each comprising a set of indexing devices, a set of digit keys for all of the registers, bars common to all the registers and operable by the digit keys for setting the indexing devices, denomination-determining mechanism, and means, including devices shiftable on the bars, for causing the bars either to set indexing devices for subtraction for one register at the operation of the keys while the bars set indexing devices for addition for another register, or to set indexing devices for the registers in succession, for either addition or subtraction in each register, at will.

65. In a computing machine, in combination, a set of parallel denominational members, each having a row of indexing devices, bars extending across said denominational members and depressible to set said indexing devices, and devices mounted on the setting bars and serving as interponents to engage said indexing devices when the setting bars are depressed, said interponents being shiftable on said setting bars to render the latter effective or ineffective on said indexing devices.

66. In a computing machine, in combination, a set of parallel denominational members, each having a row of indexing devices, bars extending across said denominational members and depressible to set said indexing devices, and interponents having teeth spaced in accordance with the spacing of the denominational members, said interponents being slidable on said setting bars to render the teeth effective or ineffective to engage the indexing devices.

67. In a computing machine, in combination, a bar mounted for reciprocation transversely thereof and having a longitudinal slot, and an interponent mounted in said slot and having teeth at denominational intervals projecting beyond the edge of said bar, said interponent being shiftable along said slot to position said teeth in or out of denominational position.
